HARRY NATKIEL AND ISADORE FREEDMAN, OF NEW YORK, N. Y.

HAIR WAVER.

Application filed March 15, 1922. Serial No. 543,827.

To all whom it may concern:

Be it known that we, HARRY NATKIEL and ISADORE FREEDMAN, both citizens of the United States, residing at New York city, 5 borough of Manhattan, in the county of New York and State of New York, have invented certain new and useful Improvements in Hair Wavers of which the following is a specification.

10 This invention relates to toilet articles and especially to devices for hair dressing purposes.

15 Among the objects of the invention is to provide a simple, easily manipulated, and reliable construction for making waves or crimps in ladies' hair, the facility with which the device may be operated depending upon certain novel details of construction hereinafter set forth.

20 More specifically, this device relates to that type of hair wavers in which a clamp like device is provided and including two leg portions extending along each other from a common point of attachment at one 25 end, while the inherent tendency of the metal or the like from which the device is made is such as to cause the free end portions of the legs to bow or bend relatively away from each other when unlocked. As made 30 heretofore however the fastening and unfastening of a device of this general character has been more or less difficult by reason of the fact that the operator's fingers have a tendency to slip while causing one 35 leg of the device to swing laterally with respect to the other.

With the foregoing and other objects in view the invention consists in the arrangement and combination of parts hereinafter 40 described and claimed, and while the invention is not restricted to the exact details of construction disclosed or suggested herein, still for the purpose of illustrating a practical embodiment thereof reference is 45 had to the accompanying drawings, in which like reference characters designate the same parts in the several views, and in which—

50 Figure 1 is a perspective view of our improved device open ready to receive a strand of hair in a well known manner around either of the legs.

Fig. 2 is a plan view of the locking end of the device closed.

55 Fig. 3 is a longitudinal section on the line 3—3 of Fig. 2.

Fig. 4 is a transverse section on the line 4—4 of Fig. 2.

Referring now more specifically to the drawings our improved construction is shown as being made of a single strip of metal of substantially uniform width and cross section and comprising two main portions or legs 10 and 11 connected to each other at one end through a loop 12 formed preferably entirely above the plane of the first mentioned leg 10. It being well understood that the clasping and unclasping of the free ends of these legs is performed as a result of relative lateral movement of the leg 11 over that shown at 10, we have discovered that by producing the loop 12 as a part only of the leg 11, this leg is more flexible for relative movement than has heretofore been the case when the loop is otherwise formed. While we show both legs curved normally away from each other, it may be expedient to form the device so that the legs of the device may be otherwise shaped. In any event in the operation of the device the strand of hair is wrapped usually around one of the legs, beginning at a point close to the loop 12 and wrapping outward toward the free end thereof. After this wrapping is done the free ends of the legs are clamped or locked together, thereby putting the strands of hair so wrapped or coiled under sufficient compression to produce a pleasing wavy effect.

The leg 10 is shown provided with its free end turned upward forming a point or hook 13, the bend being approximately circular so that the extreme point of the hook is directed downward toward the flat part of the leg adjacent to the bend. The other leg has its free end formed with a cup 14 adapted to take under the hook 13 and receive within it the extreme point thereof, the concavity of the cup serving to hold the point of the hook so as to lock the parts from relative lateral or endwise movement in practice.

One of the important features of this improvement lies in the peculiar finger grip means provided for the manipulation of the free ends of the legs. As shown the free end of the leg 10 is provided with an open slot 15 extending lengthwise thereof and into which the flesh of the operator's finger bulges when pressure is applied thereto from the bottom. In other words, as here-

tofore the operator's finger was not gripped upon this part of the device and would slip therefrom except for a possible engagement with one of the outside edges thereof, but 5 with our improvement the forcing of the flesh of her finger into this opening or slot affords a material increase of the operator's grip upon this part of the device. For a similar purpose the neck portion 16 of the 10 free end of the leg 11 is shown concaved and of oval outline, thus providing spaced relatively sharp edges 17 having an effect analogous to the action of the slot 15 and spaced to a less extent than the width of the 15 main part of the leg. It must be apparent therefore that while pressure must be applied to the free ends of the legs toward each other in causing the compression above referred to, at the same time the cup end 20 must be swung aside and brought beneath the hook 13 in order to lock the parts in clamping position, and then subsequently they are separated or unlocked by a reverse movement. The edges of the slot 15 and 25 and the edges 17 of the finger piece 16 afford the desired amount of frictional contact or engagement between the operator's fingers and these parts of the device.

We claim:

30 1. A hair waver comprising a leg having formed on the free end thereof a round

edged cup constituting an engaging member, the other leg having formed at its free end a hook co-operating with the cup, said co-operating members being dependable for 35 their action upon a relative lateral movement between the ends of the legs, and means formed on the legs adjacent to the free ends to prevent slippage of the operator's fingers while causing said lateral movement, said 40 anti-slipping means on the leg having the cup consisting of a concavity formed in such leg adjacent to but distinct from the cup and having an oval outline narrower than the main part of the leg.

2. A hair waver comprising a leg having formed on the free end thereof an engaging member, the other leg having formed at its free end a co-operating engaging member, said engaging members being dependable for 50 their action upon a relative lateral movement between the ends of the legs, and means formed on the legs adjacent to the free ends to prevent slippage of the operator's fingers while causing said lateral movement, said 55 anti-slipping means including a longitudinal slot formed in one of the legs and into which the flesh of the operator's finger bulges.

In testimony whereof we affix our signatures.

HARRY NATKIEL.
ISADORE FREEDMAN.
